UNITED STATES PATENT OFFICE.

HERMAN B. GAFFERS, OF WATERVLIET, NEW YORK.

SCAFFOLD.

Application filed August 18, 1924. Serial No. 732,868.

This invention relates to improvements in scaffolds of the type in which are employed ladder sections with other parts and detachable connecting means adapted to be 5 quickly assembled and taken down.

A serious objection to the use of present day scaffolds of this type is the difficulty experienced in obtaining rigid connections between the ladder sections through the rungs 10 thereof with other parts on account of variation in the shape and size of the ladder rungs due to unequal shrinkage of the wood of the rungs, a condition commonly met with.

The object of the present invention is to 15 provide an improved scaffold of the type referred to, to provide improved connecting means between the rungs of the ladder sections and other parts that while providing for the rapid and easy assembly of the scaffold will, at the same time, afford a rigid 20 connection between the parts, and by which the difficulty referred to is entirely avoided.

The invention, with other objects and advantages thereof, and the particular construction, combinations and arrangements 25 of parts comprising the same, will be understood from the hereinafter contained detailed description, when considered in connection with the accompanying drawings, 30 forming part hereof, and illustrating embodiments of the invention.

In the drawings:

Figure 1 is a perspective view of a section of a scaffold constructed in accordance 35 with the present invention.

Fig. 2 is a part section and side elevation, on an enlarged scale, of a part of the construction illustrated Figure 1.

Fig. 3 is a detail side elevation, on an enlarged scale, of the connecting means on one 40 end of an intermediate rail member.

Fig. 4 is a detail transverse section on the line 4—4 Figure 3.

Figs. 5 and 6 are detail perspective views 45 of members of the connecting means.

Fig. 7 is a detail side elevation illustrating a modified form of connecting means.

The invention comprehends a scaffold including a ladder section and a rail, brace, or other scaffold member associated therewith, and provided with a connecting device having a yoke part to embrace a rung of the ladder section and which is formed tapering or provided with a tapering socket 50 and is self adjusting to compensate for variation in the contour and size of the ladder

rungs, due to unequal shrinkage or other causes and will tightly clasp or clamp within the same a ladder rung and afford a firm rigid connection between the parts. The invention further contemplates a connecting device of this kind having an adjustable plate member adapted to bridge the open end of the yoke part and carrying a clamp screw to engage the ladder rungs at one 60 side and assist in holding the same in tight fitting engagement with the yoke part.

While specific embodiments of the invention are illustrated in the drawings, it will of course be understood that changes and 70 variations in the particular constructions shown, and the carrying out of the invention in other forms, as will appeal to those skilled in the art and falling within the scope of the appended claims may be practiced without departing from the spirit of 75 the invention.

The section of scaffolding illustrated in the drawings by way of example comprises vertical ladder sections A—A', an intermediate rail member B, and inclined struts or braces C—C', the rail member B and the braces C—C' being equipped with connecting devices D constructed in accordance with the present invention to embrace the rungs 80 of the ladder sections A—A'.

The particular construction of connecting device illustrated in Figures 1 to 6 of the drawings comprises a flat attaching plate portion 1 to fit against and be secured to an end portion of the rail brace or other member, and a yoke part 2 at one end of the plate portion to embrace a rung of a ladder section, the plate section 1 and yoke 2 being integral and conveniently, as shown, being 90 in the form of a casting. The yoke part 2 is provided with oppositely inclined inner side faces 2^a, 2^b converging toward the closed end 2^c thereof providing a tapering interior formation or socket widest at the open end of the yoke, the construction being self adjusting to compensate for variations and irregularities respecting the contour or size 95 of the ladder rung, tightly clasping the ladder rungs when engaged therewith and always insuring a firm rigid connection between the parts. 3 designates a plate member adjustable longitudinally of the plate portion 1 adapted to be positioned with its forward part 3^a bridging the open end of the yoke 2 or retracted to one side of the yoke, 100 said plate member 3 at its forward part 3^a

115

carrying a clamp screw 4 adapted to bear against one side of a ladder rung engaged by the yoke and to force and hold the parts in tight fitting engagement. The clamp screw 4 extends transversely of the forward part 3^a of the plate member 3, engaging a threaded opening therein, this portion of the plate member 3 being shown thickened and provided with a recess 3^b at its under side to receive the head 4^a of the clamp screw 4 when the same is adjusted to its innermost position. The plate member 3 has a reduced outer end portion 3^d to fit within a seat on the yoke 2 formed by an opening 5 in one side of the yoke when the plate member 3 is adjusted to extend across the open end of the yoke, provision thus being made for firmly holding the forward portion of the plate member to the yoke against outward displacement when the clamp screw 4 is tightened up against a ladder rung within the yoke.

The plate portion 1 is provided at one side with a longitudinally extending boss or raised part and an elongated slot 6 extending through the plate portion and boss. The plate member 3 is slotted at 3^c, as shown, to fit over and slidably engage the boss. The boss has a rear portion 7 of less thickness than the forward part 7^a thereof, and the plate member 3 is of a thickness less than the thickness of the forward portion 7^a of the boss and greater than the thickness of the rear portion 7 of the boss. The means for securing the connecting device to the intermediate rail member B, braces C, or other scaffolding members, comprises a pair of bolts 8, 9, extending through the scaffolding member and the elongated slot 6 of the plate portion 1. The bolts 8, 9, are spaced as shown, at opposite ends of the slot 6, the bolt 8 extending adjacent the forward part 7^a of the boss, and the bolt 9 being located adjacent the reduced rear portion 7 of the boss. 8^a designates a nut on the bolt 8 to remain tightly turned up to clamp the plate portion 1 to the scaffolding member, a washer 10 being shown interposed between the nut 8^a and the thicker portion 7^a of the boss, the washer being shown of a size to project over but free of the side portions of the plate member 3. The plate member 3 is adjustably secured to the plate portion 1 by means of a winged clamping nut 11 and washer 12, the winged nut 11 when tightened up clamping the plate member 3, through the washer 12, against the upper face of the plate portion 1. As will be understood by loosening the winged nut 11 the plate member 3 will be free for sliding movement on the plate portion 1 and may be adjusted as desired to bridge the open end of the yoke or adjusted to a position to one side thereof.

In many instances in which the arrangement of the intermediate connecting rails,

braces, or other scaffolding members which are provided with the connecting devices is such that the weight or forces tend to force the yoke into engagement with the ladder rung, the clamping screw is not essential, and the invention comprehends constructions in which the clamp screw is not employed, such a modified construction being illustrated in Figure 7 of the drawings, the construction illustrated in this view being the same as that shown in Figures 1 to 6 of the drawings, except that the same does not have a clamp screw carried by the adjustable plate member. In Figure 7, illustrating the modified construction, 14 designates an intermediate rail member to which is secured by screws 15, 16, the connecting device comprising the plate portion 17, yoke 18, and adjustable plate member 19, the latter in this instance simply acting as a guard.

It will be noted that by the particular construction and arrangement of parts hereinbefore set forth connecting means of a simple efficient nature is afforded capable of being quickly engaged with and detached from the ladder rungs, providing for the rapid assembling and taking down of the scaffolding, and at the same time the construction is such as to always insure rigid connections between the parts, the device being self adjusting or readily accommodating itself to variations or irregularities in the ladder rungs so that such variations or imperfections do not effect the rigidity of the scaffolding.

What I claim is:

1. A scaffold including a ladder section, a rail member associated therewith, and connecting means on the rail member including a plate portion to fit against a face of the rail member with a yoke at one end of the plate portion to tightly embrace a rung of the ladder section, said yoke having oppositely inclined inner side faces converging toward the closed end thereof, and said yoke at one side having a seat located inwardly of the outer end of the side of the yoke and extending inwardly of the side of the yoke, a plate member mounted on said plate portion for adjustment longitudinally thereof and adapted to be positioned to bridge the open end of the yoke with one end extending into the said seat on the yoke, a clamp screw carried by and extending transversely through the plate member near one end thereof to engage and tightly hold a rung of the ladder section in engagement with the inclined inner side faces of the yoke, means for securing the plate portion to the rail member, and means for adjustably securing the plate member to the plate portion.

2. A scaffold including a ladder section, a rail member associated therewith, connecting means on the rail member including a

plate portion to fit against a face of the rail member, and a yoke at one end of the plate portion to embrace a rung of the ladder section, said plate portion having a 5 longitudinally extending boss at one side and being provided with a slot extending through the same and the boss, a plate member adapted to bridge the open end of the yoke, the plate member being provided with 10 a longitudinal slot to fit over said boss and being slideable on said plate portion, said boss having a portion thereof of greater thickness than the plate member and projecting above the outer face thereof, and the boss 15 having a section of less thickness than that of the plate member, and means for securing the plate portion to the rail member and for adjustably securing the plate member to the plate portion, said means comprising 20 a pair of bolts extending through the rail member, the slot of the plate portion, and the slot of the plate member, one of said bolts being located adjacent the thicker portion of the boss, and the other bolt being located 25 adjacent the thinner portion of the boss, and clamp nuts on the bolts.

3. A scaffold including a ladder section, a rail member associated therewith, and connecting means on the rail member including a plate portion fitting against a face of the rail member and having a U-shaped yoke at one end thereof adapted to tightly clamp a rung of the ladder section between the side walls thereof, said yoke having straight inner side walls of substantial length extending from the outer end thereof to its bottom part at a substantial inclination toward each other and converging toward the bottom part of the yoke, and the space between the said inclined side walls relative to the diameter of the rung of the ladder section being such as to compensate for variations in the cross sectional size of the rung of the ladder section so that when the yoke is engaged with the rung under pressure, the rung will be spaced from the inner bottom part of the yoke and held wedged between the inclined side walls thereof to provide a rigid connection between the parts.

In testimony whereof I hereunto affix my signature.

HERMAN B. GAFFERS.
